(57) **CLAIM**

The ornamental design for a support chair for poured concrete reinforcement members, as shown and described.

DESCRIPTION

FIG. 1 is a perspective view, taken from the top, front, and side, of a support chair for poured concrete reinforcement members, in accordance with a first embodiment of our new design.

FIG. 2 is a front elevation view of the support chair for poured concrete reinforcement members shown in FIG. 1. FIG. 3 is a rear elevation view of the support chair for poured concrete reinforcement members shown in FIG. 1. FIG. 4 is a right side elevation view of the support chair for poured concrete reinforcement members shown in FIG. 1. FIG. 5 is a left side elevation view of the support chair for poured concrete reinforcement members shown in FIG. 1. FIG. 6 is top plan view of the support chair for poured concrete reinforcement members shown in FIG. 1.

FIG. 7 is a bottom plan view of the support chair for poured concrete reinforcement members shown in FIG. 1.

FIG. 8 is a perspective view, taken from the top, front, and side, of a support chair for poured concrete reinforcement members, in accordance with a second embodiment of our new design.

FIG. 9 is a front elevation view of the support chair for poured concrete reinforcement members shown in FIG. 8. FIG. 10 is a rear elevation view of the support chair for poured concrete reinforcement members shown in FIG. 8. FIG. 11 is a right side elevation view of the support chair for poured concrete reinforcement members shown in FIG. 8. FIG. 12 is a left side elevation view of the support chair for poured concrete reinforcement members shown in FIG. 8. FIG. 13 is top plan view of the support chair for poured concrete reinforcement members shown in FIG. 8; and, FIG. 14 is a bottom plan view of the support chair for poured concrete reinforcement members shown in FIG. 8.
